[57] **ABSTRACT**

A machine for the non-cutting forming of metal in a hammer forging machine having a feed device for rotatingly feeding the material to the machine, in which clamping means is mounted on the machine frame and coordinated with the hammer machine, and is alternately driven by a hydraulically and mechanically acting mechanism towards the tools of the machine.

MACHINE FOR NON-CUTTING FORMING OF METALS

The present invention relates to a machine for the non-cutting forming of metals in a hammer forging machine into which the metal is fed rotatingly.

In such machines, the combined effect of the hammering (impact) forming operation in addition to the upsetting (jolting) forming operation, causes a certain amount of recoil to occur in an opposite direction to the rotating material feed. Such recoil will considerably impair any hammering or upsetting forming operation.

An object of the invention is the elimination of such recoil during hammering or upsetting metal forming as much as possible, i.e., recoil acting in opposite direction to the material feed. Accordingly, the present invention provides a rotatable clamping means mounted on the machine frame, and coordinated with the hammer machine, which is driven alternately toward the tools by a hydraulically and then a mechanically driven feed mechanism.

Other objects and features of the present invention will become apparent from the following detailed description when taken in connection with the accompanying drawing which discloses an illustrative embodiment of the invention. It is to be understood that the drawing is designed for the purpose of illustration only, and is not intended as a definition of the limits and scope of the invention.

Turning now to the drawing, there is shown a machine for the non-cutting forming or shaping of metals which comprises a hammer forging machine 1 provided with impact tools 2. An clamping means 4 is coordinated with the hammer machine 1, 2, on the machine frame 3 and is driven alternately toward the tools by a hydraulically and mechanically operating feed mechanism. In order to provide an upsetting forming operation and a rotating material feed, clamping means 4, which is driven by the hydraulically and alternately mechanically working feed mechanism, comprises a clamping device 5 which holds the material to be fed, and is equipped with a motor-driven rotating device 6. The mechanically acting feed mechanism, in its interior, is designed as a hydraulically acting feed mechanism. The mechanically acting feed mechanism consists of a hollow, non-revolving, axially movable spindle 7 having a threaded exterior portion which engages the internal threads a rotatably driven and frontally supported adjustment collar 8. This adjustment collar 8, in its housing 9, is frontally supported by thrust bearing 10 and rotatably mounted thereon. The rotary drive for the adjustment collar 8 is derived from a motor-driven chain drive 11. The plunger or piston 12 of a tubular piston rod 13 slides along the cylindrical interior wall of the hollow threaded spindle 7. The bar or rod stock is guided towards the hammer unit 1, 2 by means of the tubular rod. At the end of its forward or feed stroke, which is designed for rapid motion, the hydraulically acting feed mechanism 12, 13 is disconnected and blocked in the cylindrical threaded spindle 7, as well as rigidly connected with the mechanically acting feed device 7 - 11 which, at that moment is engaged. This causes the mechanically acting mechanism 7 - 11 to axially displace the rotatably driven clamping means 4 - 6, over the hydraulic drive 7, 12, 13, against the hammering device 1, 2. A switch mechanism, for the disengagement of the hydraulically acting feed mechanism 7, 12, 13 - whereby a blocking effect is attained - and its rigid connection to the engaged mechanically acting feed mechanism 7 - 11, is depicted schematically in the drawing.

gagement of the hydraulically acting feed mechanism 7, 12, 13 - whereby a blocking effect is attained - and its rigid connection to the engaged mechanically acting feed mechanism 7 - 11, is depicted schematically in the drawing.

In the hollow spindle cylinder 7, at both sides of the plunger 12, there are feed and drain ducts 14 and 15 for a hydraulic pressure agent, which lead towards a pump 16. Pump 16 is reversible to provide alternate generation of a high or low pressure, i.e., a super-atmospheric pressure and a vacuum. In duct 15 there is a spring-loaded and manually operated valve 17 which blocks the flow-back of the pressure fluid from spindle cylinder 7 to pump 16. A branch duct 18 leads from duct 15 to a reversible electric switch 19 for reversible motor drive 22 for rotary drive 8 - 11 of adjustment collar 8, and its housing 9 is rigidly mounted on the machine frame.

In the initial stage of a metal forming operation, a machine equipped according to the present invention is in the position shown in the drawing. Mechanical drive 11, 12 for adjustment collar 8 is disengaged, so that the hollow, cylindrical threaded spindle cannot be shifted axially. Pump 16 is switched to generate pressure. This causes the valve to open and pressure fluid to flow into spindle cylinder 7, thus pushing the piston or plunger forward, whereby hollow piston rod 13, in rapid motion, moves or transports clamp carrier means 4 - into operational position in front of hammer machine 1, 2. The air present at the side of the piston which is not under pressure, thus, can escape through duct 14 from the spindle cylinder.

At the end of the rapid-motion forward stroke of the hydraulically acting feed mechanism 12, 13, piston 12 abuts cylinder head 20 of spindle cylinder 7. This causes high pressure to be generated in pressure chamber 21 of spindle cylinder 7 and in the pressure duct 15 on both sides of valve 17. This high pressure actuates the electric switch 19 governing drive 8 - 11 of check nut 8 and causes spring-loaded valve 17 to close. The hydraulically acting feed mechanism 12, 13 is disengaged and blocked in spindle cylinder 7, since a backward flow of the pressure fluid from pressure chamber 21 through the closed valve is impossible. At this point, the mechanically acting drive for the rotary feed of the material (bar stock) is operative with rotary drive 4, 5, 6 of the clamping means during non-cutting metal forming, so that recoils from the clamping means are absorbed and neutralized by adjustment collar 8.

When the metal forming operation is completed, valve 17 is locked in its open position and pump 16 is reversed so as to generate low pressure (partial vacuum). The partial vacuum generated via opened duct 15 in pressure chamber 21 and branch duct 18 causes hydraulically acting feed mechanism 12, 13 to return to its initial position and to reset electric switch 19, so that mechanically acting feed mechanism 7 - 11 and 22 moves back to its starting position. It is expedient that, for the interruption of the material feed during the striking power stroke of the tools, a conventional friction or similar clutch is provided between clamping device 4, 5 and its rotary drive 6. This guarantees that the quality of the metal forming during rotary material feed is not impaired.

While only a single embodiment of the present invention has been shown and described, it will be obvious to those persons skilled in the art that many changes

and modifications may be made thereunto without departing from the spirit and scope of the invention.

What is claimed is:

1. In a machine for feeding metal stock to a hammer forging device the improvement which comprises in combination:

a clamping means for gripping said metal stock and coupled to a combination hydraulic and mechanical drive mechanism adapted to provide reciprocating motion of said clamping means relative to said forging device and comprising a screw spindle feeder, and a hydraulic feeder capable of rapid motion and provided with a blocking means for blocking the hydraulic feeding action and rigidly connecting said screw spindle feeder to said clamping means at the end of the forward stroke of said hydraulic feeder.

2. A machine according to claim 1 in which said drive mechanism is equipped with automatic means for blocking the hydraulic feeding action and substantially simultaneously activating the screw spindle feeder.

3. A machine according to claim 1 in which movable elements of said hydraulic feeder are located inside

said screw spindle feeder.

4. A machine according to claim 1 in which said screw spindle feeder comprises a nonrotatable, axially displaceable spindle having an external thread engaging an internal thread of a rotatable driving and adjusting collar mounted in a stationary housing.

5. A machine according to claim 3 in which said clamping means is connected to a piston rod of a hydraulic piston slidably mounted within a hollow spindle of said screw spindle feeder.

6. A machine according to claim 1 in which a motor drive means is provided for rotating said clamp means.

7. A machine according to claim 6 in which the rotary drive means is provided with a friction clutch for interrupting rotation of said stock during hammer strokes of said forging device.

8. A machine according to claim 2 in which said clamp means is connected to a piston rod attached to a hydraulic piston slidably mounted inside a nonrotatable hollow spindle of said screw spindle feeder and said spindle is axially displaceable by means of an external thread thereon engaging the internal thread of a driving and adjusting collar supported within a stationary housing.
